US0D1049019S

(12) **United States Design Patent** (10) Patent No.: **US D1,049,019 S**
(45) Date of Patent: ** Oct. 29, 2024

(54) **SOLAR POWER FOR CHARGING PACK**

(71) Applicant: **Shanghai Gotion New Energy Co., Ltd.**, Shanghai (CN)

(72) Inventors: **Chang Soo Lee**, Shanghai (CN); **Liuwei Mai**, Shanghai (CN); **Changcheng Ma**, Shanghai (CN); **Jinxi Shen**, Shanghai (CN); **Bo Zhao**, Shanghai (CN)

(73) Assignee: **Shanghai Gotion New Energy Co., Ltd.**, Shanghai (CN)

(**) Term: **15 Years**

(21) Appl. No.: **35/516,892**

(22) Filed: **Mar. 2, 2023**

(57) **CLAIM**

The ornamental design for a solar power for charging pack as shown and described.

DESCRIPTION

1.1: Front

1.2: Back

1.3: Left

1.4: Right

1.5: Top

1.6: Bottom

1.7: Perspective

1.8: Perspective

The use of the present design product: photovoltaic power generation and power supply for external equipment; The design gist of the present design product: the shape of the product; The picture or photo best showing the design gist of the present design product: perspective view 1; FIG. 8 is schematic structural view of the flat solar panel after the photovoltaic package is unfolded.

(Continued)

Broken lines show portions of the solar power for charging pack that form no part of the claimed design.
